UNITED STATES PATENT OFFICE.

MILTON EUGENE BLUME, OF NEW YORK, N. Y.

COPY-HOLDER FOR TYPEWRITERS.

1,345,986.

Specification of Letters Patent.

Patented July 6, 1920.

Application filed November 24, 1917. Serial No. 203,808.

To all whom it may concern:

Be it known that I, MILTON EUGENE BLUME, a citizen of the United States, and resident of New York, in the county of New York and State of New York, have invented certain new and useful Improvements in Copy-Holders for Typewriters, of which the following is a specification.

This invention relates to improvements in copy holders for typewriters and has as its principal object the provision of a device, that may be attached to the frame of a typewriter, which will display the copy so it will always be in front of and visible to an operator.

A further object is to provide means for shifting the copy at will; also to display one or more lines of the copy as is desired. Another object is to provide means whereby the copy holder may be folded over the typewriter, when not in use, so as to economize space.

A still further object of the invention is to provide guides for the copy paper which will direct the paper properly into operating parts of the device and also prevent the copy paper from interfering with the typewriter itself.

These and other like objects are attained by the novel construction and combination of parts hereinafter described, and shown in the accompanying drawings, forming a material part of this invention, the particular features of novelty constituting the invention being pointed out in the claims hereof.

In the drawings, in which like figures of reference refer to similar parts wherever they occur:

Fig. 1 is a front elevational view, showing the invention.

Fig. 2 is a side elevational view of the same.

Fig. 3 is a transverse sectional view taken on line 3—3 of Fig. 1, and

Fig. 4 is a fragmental sectional detail of the paper engaging parts, partly broken away in order to show the construction more clearly; and

Fig. 5 is a fragmental front elevation of a typewriter showing my invention applied thereto.

In the drawings the numeral 10 indicates a pair of opposed feet adapted to be secured to the rear upper part of a typewriter frame. Engaged therewith by hinged joints 11, are

bent support bars 12, connected by a transverse rail 13, forming a supporting frame for the parts below described, the bars having secured to them horizontal arms 14, in which is journaled an operating shaft 15, provided with a turning knob 16, beyond the arm, while extending between the arms, secured to the shaft, is a feed roller 17 covered with rubber or similar material.

A compression roller 18 is also mounted in slots formed in the arms, and may be moved to or from the feed roller 17 by hook connections 19, engaged with cams 20, mounted upon a transverse spindle 21, also journaled in the arms 14, and which is turned by operating the lever 22, both the cam carrying spindle and the compression roller being housed in the casing 24, secured by brackets 25 to the support bars 12, in which is also secured a guide plate 26, turning angularly toward the front, which is adapted to direct the paper 27 to the feed roll. A curved paper guide 28 is hinged by the pin 29 to the lower edge of the casing 24, and serves to guide the copy paper projecting from between the rollers and to keep the same from interfering with parts of the typewriter and also as a screen to coöperate with the screen 37, below described, to screen from the view of the operator all of the copy except that portion thereof being transcribed. Springs 30 are engaged with the supporting frame and the extending ends of the compression roller so that the latter is normally held against the feed roller.

Also supported by the support bars 12, by means of brackets 32, is a curved plate 35, the ends 36 of which are turned toward the front, and engaged with the same is a screen 37 operable vertically with relation to the support plate by means of racks 38 engaging with spur pinions 39 secured to a shaft 40, rotatably mounted in bearings 41, the shaft having an extending knob 42, so that by turning said knob the screen 37 is caused to move parallel and uniformly, so as to disclose at will one or more lines of the matter to be copied.

The upper edge of the screen 37 is bent backwardly to form a paper guide 37a as shown in Fig. 3.

In order to rotate the paper feed roll 17, a ratchet wheel 45 is secured to the shaft 15, and engageable with it is a pawl 46, normally pressed forward by a spring 47.

secured to one of the support bars 12, the pawl having an extending pin 48 by means of which it can be withdrawn from engagement with the ratchet. This pawl is pivotally engaged at its lower end with the top of a bar 50, slidably engaged in a bearing 51 formed with the adjacent support bar, and is pivoted at its lower end to a link 52, having a plurality of slots 53 in its lower end, engageable with a pin 54 set in the end of a lever 55, fulcrumed at 56, and having at its outer end a button or key 58 by means of which the lever may be depressed, it being normally held in a raised position by the spring 59, which is of sufficient tension to actuate the feed roll when the lever is released.

Journalized at the top of the support bars 12 is a spindle 60 having secured at its ends disks 61 and an operating knob 62, said disks containing openings 63, through which pins may be passed from the arms 64, said arms carrying at their extremities a rod 65, upon which is secured a plate 66 formed with a turned lower edge 67, receptive of a thin book such as is used by stenographers, the leaves of which are held against the plate by a slide 70 having a longitudinal slot 72 through which the copy is disclosed, and which is held in any desired adjustment on the plate by means of the flat springs 73, carried by the slide in contact with the back of the plate opposite to the guide edges 74, thus permitting the slide to be adjusted as desired.

In Fig. 5 I illustrate an important feature of my invention, showing that all the copy in the copy-holder is screened from view with the exception of that portion that is actually being copied. Also that the line of matter 100, that is being copied, is held at all times in vertical alignment with the line being written by the typewriter, or, in other words, with the striking point of the type against the platen of the typewriter as shown at 101.

It will be obvious that the element 28, while serving as a guide for the copy paper, also acts as a screen for the copy on that portion of the copy paper that projects invariably beneath the feed and compression rollers, and that said element 28, and the screen 37 together effectually screen all the copy except that portion of the same that is intentionally exposed to be copied.

In operation, the feet having been secured on a typewriting machine, the support bars are extended as shown and locked in position by the slotted sliding plate 76, which engages with a stud or screw heads 77 when in use, or which permits the structure to be folded over the machine when not required.

Paper is inserted in front of the plate 35 and the knob 16 operated to feed the same

as desired, after which the button or key 58 may be actuated producing the same result. The plate 37 is then adjusted to show one or more lines of the copy, or if a copy book is used, the support plate 66 is turned 70 forward and used in the manner indicated.

From the foregoing it will be seen that a convenient device for holding the copy has been disclosed, and that one or more lines may be shown as is desired, and that 75 the copy can be moved in a convenient manner by the operator.

It will also be seen that the copy is in the best possible position to be viewed by an operator and that the same may be readily attached to any machine.

Having thus described my invention, what I claim as new and desire to secure by Letters Patent, is:

1. A copy holder comprising a support- 85 ing frame, a feed roller and a compression roller mounted in said frame, a fixed guid- ing member extending upwardly from a point adjacent the meeting line of said feed and compression rollers, and an adjustable 90 guiding and screening member disposed in front of said fixed guiding member and having its bottom edge a short distance above the said compression roller, a rack secured to said screening and guiding mem- 95 ber, a pinion engaging said rack, and means whereby said pinion may be rotated.

2. A copy holder comprising a support- 100 ing frame, a feed roller and a compression roller mounted in said frame, a fixed guid- ing member extending upwardly from a point adjacent the meeting line of said feed and compression rollers, an adjustable guid- ing and screening member disposed in front of said fixed guiding member and having its 105 bottom edge a short distance above said compression roller, a second guiding member disposed below the said rollers, and a sec- 110 ond guiding and screening member located in front of the second guiding member and having its lower end curved inwardly toward said second guiding member.

3. A copy holder comprising a support- 115 ing frame, a feed roller and a compression roller mounted in said frame, a fixed guid- ing member extending upwardly from a point adjacent the meeting line of said feed and compression roller, an adjustable guid- ing and screening member disposed in front of said fixed guiding member and having 120 its bottom edge a short distance above said compression roller, a second guiding mem- 125 ber disposed below the said rollers, and a second guiding and screening member located in front of the second guiding mem- ber, and having its lower end projecting below and curving under the said second guiding member.

4. A copy holder comprising a support- 130 ing frame, a feed roller and a compression

- roller mounted in said frame, a fixed guiding member extending upwardly from a point adjacent the meeting line of said feed and compression roller, an adjustable guiding and screening member disposed in front of said fixed guiding member and having its bottom edge a short distance above said compression roller, a second guiding member disposed below the said rollers, and a second guiding and screening member located in front of the second guiding member, and having its lower end projecting below and curving under the said second guiding member, said second guiding and screening member having its upper end extending inwardly over the said compression roller below the first guiding and screening member to close proximity to the first guiding member.
5. A copy holder comprising a supporting frame, opposed feed and compression rollers rotatably supported therein, a shaft extending adjacent and parallel to the said compression roller, a member hooked at each 20 end and taking over the said shaft and the journaled member of the said compression roll, a cam upon the said shaft adapted upon rotation of the shaft to draw the said compression roller away from the feed roller, means whereby said shaft may be rotated, and a spring holding said compression roller against said feed roller.
6. A copyholder comprising a frame adapted to be attached to a typewriter, means whereby said frame may be folded upon itself or extended vertically, a feed roller mounted transversely in said frame, a compression roller mounted parallel with and contiguous to said feed roller, means for 25 normally exerting pressure between said frame and compression roller, means for releasing said pressure, a guide extending below said feed roller, means extending toward the front of the typewriter and through which said feed roller may be actuated, a paper guide receptive of the copy, a screen slidably engaged on said paper guide whereby an opening is formed through which one or more lines of copy may be displayed, and means for actuating said screen whereby the extent of the opening may be modified.
7. A copyholder comprising a supporting frame adapted to be secured to a typewriter, a feed roller journaled in said frame, a compression roller mounted to resiliently engage said feed roller, a spindle mounted transversely in said frame, cams secured on said spindle at the ends thereof, connections between said cams and said compression roller whereby the latter may be moved to or from said feed roller, means for guiding the copy paper before and after engagement with said feed roller, a movable screen receptive of the copy arranged at the front of said copy holder, and means for actuating said screen whereby one or more lines of copy may be disclosed, and means for operating said feed roller in either direction whereby the copy may be raised or lowered.
- 20 5. A copy holder comprising a supporting frame, opposed feed and compression rollers rotatably supported therein, a shaft extending adjacent and parallel to the said compression roller, a member hooked at each end and taking over the said shaft and the journaled member of the said compression roll, a cam upon the said shaft adapted upon rotation of the shaft to draw the said compression roller away from the feed roller, means whereby said shaft may be rotated, and a spring holding said compression roller against said feed roller.
6. A copyholder comprising a frame adapted to be attached to a typewriter, means whereby said frame may be folded upon itself or extended vertically, a feed roller mounted transversely in said frame, a compression roller mounted parallel with and contiguous to said feed roller, means for 25 normally exerting pressure between said frame and compression roller, means for releasing said pressure, a guide extending below said feed roller, means extending toward the front of the typewriter and through which said feed roller may be actuated, a paper guide receptive of the copy, a screen slidably engaged on said paper guide whereby an opening is formed through which one or more lines of copy may be displayed, and means for actuating said screen whereby the extent of the opening may be modified.
7. A copyholder comprising a supporting frame adapted to be secured to a typewriter, a feed roller journaled in said frame, a compression roller mounted to resiliently engage said feed roller, a spindle mounted transversely in said frame, cams secured on said spindle at the ends thereof, connections between said cams and said compression roller whereby the latter may be moved to or from said feed roller, means for guiding the copy paper before and after engagement with said feed roller, a movable screen receptive of the copy arranged at the front of said copy holder, and means for actuating said screen whereby one or more lines of copy may be disclosed, and means for operating said feed roller in either direction whereby the copy may be raised or lowered.

Signed at New York, in the county of New York, and State of New York, 27th day of October, A. D. 1917.
